UNITED STATES PATENT OFFICE.

GEORGE W. BENT, OF HYDE PARK, MASSACHUSETTS.

FOLDING OR MANTEL BED.

SPECIFICATION forming part of Letters Patent No. 392,178, dated November 6, 1888.

Application filed March 17, 1888. Serial No. 267,482. (No model.)

To all whom it may concern:

Be it known that I, GEORGE W. BENT, of Hyde Park, county of Norfolk, State of Massachusetts, have invented an Improvement in 5 Folding or Mantel Beds, of which the following description, in connection with the accompanying drawings, is a specification, like letters on the drawings representing like parts.

This invention relates to folding beds of that 10 class known as "mantel-beds," and has for its object to provide a mantel-bed with a folding foot-board and a flexible mattress secured to the folding foot-board above its pivot, whereby when the bed is unfolded the said flexible 15 mattress automatically places the feet of the foot-board in correct position, substantially as will be described.

Figure 1 by full lines shows a longitudinal section of a mantel-bed embodying my invention 20 and ready for use, it being represented by dotted lines in the position occupied by it when folded up and not in use. Figs. 2 and 3 are details to be referred to, and Fig. 4 a section of Fig. 3 on line *x x*.

25 The frame to support the usual mattress, *a*, of woven wire or canvas or other material, consists, as herein shown, of two independent sections, *a'* *a''*, joined together by hinges *a'*, only one of which is shown in Fig. 1. The section 30 *a'* is pivoted, as at *a'*, to the sides of a case, *B*, provided with a top or shelf, *b'*, within which the folding bed-frame is concealed by suitable curtains (not shown) or in other suitable manner when the said bed-supporting frame is folded up and not in use.

35 The section *a'* of the bed-supporting frame is provided with legs or feet *b'*, only one of which is shown, the said feet being hinged at *b'* to a slat or board, *b'*, secured to the sides 40 of the section *a'*, the said feet having secured or otherwise firmly fastened to them a cross-board, *b'*, forming the foot-board of my improved mantel-bed.

45 The section *a'* of the bed-supporting frame is provided, as shown, with suitable slats, *b'*, to which are attached, as shown, spiral springs *b'*, upon which rests the mattress *a*.

50 The section *a'* is provided, as shown, with legs *c*, only one being shown in Fig. 1, which are preferably hinged to one of the slats *b'*, each leg *c* having pivotally connected to its

lower end, as at *c'*, a bar, *c''*, hinged at its opposite end, as shown at *c''*, to a cross-bar, *c''*, of the case *B*.

The mattress *a* has its ends connected to the 55 folding frame, so that when the said frame occupies the position shown by full lines, Fig. 1, ready for use, the said mattress will be below the pivots of the hinges joining the sections, thus exerting a downward pull upon the section *a'* and maintaining the said section on the floor. When the section *a'* is folded over and upon the section *a'*, the foot-board *b'* and feet *b'* are permitted by the hinges *b'* to lie flat or substantially parallel to the mattress, said 60 foot-board when in this position, as shown by dotted lines, Fig. 1, forming a space, *d*, for the reception of the pillows. By hinging the feet *b'* to thus form a folding foot-board, as described, a very considerable economy in space 65 is effected, so that when the folding bed-frame is turned on its pivots *a'* up into its dotted-line position within the case *B* it occupies very little space, it presenting a neat and compact appearance.

70 The case *B* may, if desired, have hinged to each of its sides a leg or foot-board, *d'*, only one being shown in Fig. 1, which is joined, as shown, by a chain or other connection, *d'*, to the bar *c'*, so that when the bed is folded up 75 into its dotted-line position the legs or foot-boards *d'* are turned inward substantially at right angles to the sides of the case, the said legs or foot-boards being turned outward or into the position shown by the sides of the section *a'* as the bed is lowered.

75 The legs or feet *b'* are prevented from being turned outward when the bed is lowered or in its full-line position by the foot-board *b'* striking against the sides of the section *a'*, the said legs or feet being drawn up against the sides of the said sections by the tension of the mattress, thus preventing the legs from folding under the bed.

80 The top *b'* of the case is made detachable to 85 economize space when the bed is packed for transportation, the said top, which when attached to the case forms a shelf or support for books, &c., having secured to its under side castings *e*, one for each post *e'* of the case *B*, 90 there being only one post and one casting shown in Fig. 1 and in section, Fig. 4. Each

casting e is provided with a socket, into which the end of the post e' extends, as shown in Fig. 4, the said casting having a flange, e^2 , to which the top board or shelf is screwed or otherwise fastened.

5

I claim—

1. In a folding or mantel bed, the combination of a head-section and a foot-section pivotally secured thereto, and having a folding foot-board, with a flexible mattress secured to the head-section and to the hinged foot-board above its pivot, whereby when the bed is unfolded the said flexible mattress automatically places the feet of the foot-board in correct position, substantially as described.

10

15

2. In a folding or mantel bed, a case, B, a mattress-supporting frame consisting of sections a' a^2 , pivotally connected together, the section a' being pivoted to the case B, combined with a folding foot-board secured to the section a^2 , and a flexible mattress supported only by the head-section and folding foot-board, substantially as and for the purpose specified.

20

In testimony whereof I have signed my name to this specification in the presence of two subscribing witnesses.

GEORGE W. BENT.
